SELF-RIGHTING CONTAINER

William H. Hester, Jr., Ponca City, Okla., assignor to
A. E. Warnberg, Oklahoma City, Okla.

Application April 14, 1958, Serial No. 728,487

3 Claims. (Cl. 222—463)

This invention relates to improvements in self-righting containers for storing liquids, and more particularly, but not by way of limitation, to an improved self-righting oil can.

Practically all present day liquid containers are provided with a flat bottom, such that the containers must be rather carefully placed in a vertical position when deposited on a shelf or table to prevent the container from tipping over. Thus, substantial care must be taken to assure that the container is setting in a vertical position to prevent spilling the contents therefrom. Several attempts have been made to construct various types of containers, such that the containers will not tip all the way over when the user does not take special care in depositing the container on a shelf or the like. In each instance, however, such prior efforts have involved the use of attaching guards or the like to the container which extend outwardly from the container and contact the supporting surface as the container is tilted. For example, it has been proposed to provide an oil can with an outwardly extending ring secured to the upper portion of the can, or the lower end portion of the oil can spout, which extends outwardly a greater distance than the largest diameter of the can. In this way, the outwardly extending rim will contact the supporting surface when the can is inadvertently tilted, to prevent the can from tilting all the way over and spilling oil out of the spout. However, when such stabilizing devices are used, the can necessarily occupies a larger storage area than would otherwise be required, and such auxiliary devices are expensive to manufacture and assemble on the cans.

The present invention contemplates a novel container having a weighted and rounded bottom portion constructed in such a manner that the container may be tilted to a substantial angle, and yet will right itself when released by the user. The diameter of the weighted base portion is no larger than the normal diameter of the main body portion of the container, and only slightly increases the overall height of the container, such that the self-righting container will occupy substantially the same storage space as a non-self-righting container. The present invention is particularly useful in connection with oil cans, however a similar concept may be used with other types of containers having restricted outlets in the upper ends thereof and which are formed out of a material which will not be easily broken.

An important object of this invention is to provide a liquid container which will right itself when inadvertently tilted with respect to its supporting surface.

Another object of this invention is to provide a self-righting container for liquids which will occupy substantially the same storage space as a conventional container.

A further object of this invention is to provide a self-righting container for liquids which has no obstructions extending outwardly from the sides or upper portion of the container which would interfere with the normal use of the container.

Another object of this invention is to provide a self-

2

righting oil can wherein oil may be ejected by pushing on the bottom of the can in the normal fashion, yet the lower end of the can will be weighted and rounded to provide a self-righting container.

5 A still further object of this invention is to provide a self-righting container for liquids which is simple in construction and may be economically manufactured.

Other objects and advantages of the invention will be evident from the following detailed description, when 10 read in conjunction with the accompanying drawings which illustrate my invention.

In the drawings:

Figure 1 is an elevational view, partially in section, of an oil can constructed in accordance with the present invention.

Figure 2 is a vertical sectional view through the lower end portion of a modified oil can constructed in accordance with this invention.

Figure 3 is a vertical sectional view through still another modified oil can constructed in accordance with this invention.

Figure 4 is an elevational view, partially in section, of another form of container constructed in accordance with this invention.

25 Referring to the drawings in detail, and particularly Fig. 1, reference character 6 generally designates a self-righting oil can comprising a hollow body 8 and a novel base portion 10. The hollow body 8 may be of any desired configuration, but is preferably circular in cross-section in the manner of present day oil cans. The upper wall 12 of the body 8 is extended upwardly at 14 and provided with an opening or aperture 16 having a diameter substantially less than the inner diameter of the lower portion of the body 8. The portion 14 of the upper wall 30 12 which is extended upwardly is crimped or grooved to provide threads which receive a cap member 18 formed on the lower end of a conventional oil can spout 20. The spout 20 is hollow and tapered toward its upper end to discharge oil from the can 6 to a localized area. The bottom 22 of the body 8 is flat and formed out of a flexible material, such as a metal having a thickness less than the remainder of the body 8, in order that oil may be forced out of the can 6 through the spout 20 by the user pressing upwardly on the bottom 22.

40 45 The upper end of the base member 10 has substantially the same outer diameter as the outer diameter of the body 8 and is secured to the lower end of the body 8 in any desired manner. For example, a ring or bead 24 may be secured around the lower edge of the body 8, and a flange 26 formed around the upper end of the base member 10 of a size to be crimped over the bead 24 and rigidly secure the base member 10 to the body member 8. However, the base member 10 may be secured to the body member 8 in any other desired manner, such as by welding. The side walls 28 of the base member 10 are curved downwardly and inwardly from the connection of the base member 10 to the body member 8 on a radius at least as great as one-half the radius of the body member 8, and preferably on a radius equal to about one-third of the diameter of the body member 8 to provide a substantial supporting surface for the can 6 when the can is tilted, as will be more fully hereinafter set forth.

45 50 55 60 65 70 The side walls 28 are therefore extended downwardly and inwardly to form the bottom of the base member 10, and an aperture 30 is formed in the bottom of the base member 10 having a diameter sufficiently large to receive the thumb of the user of the can. A ring 32 is secured in the aperture 30 and extends upwardly into connection with an annular plate 34 extending outwardly into connection with the side walls 28 adjacent the upper end of the base member 10. The ring 32 and plate 34 may be brazed or welded together and to the side walls

28 to form a closed annular chamber 36 extending around the axis of the aperture 30. A weighting material 38, such as sand or the like, is deposited in the chamber 36 to provide a ballast for the can 6. A sufficient amount of the weighting material 38 is provided in the chamber 36 to position the center of gravity of the entire can 6 below the bottom 22 of the body member 8, such as at the point designated by X. The center of gravity X is, of course, centrally located with respect to the can 6, since the weighting material 38 is evenly distributed around the base member 10.

In use of the can 6, the can is substantially filled with oil in the normal fashion, and the oil is discharged through the spout 20 by the user inserting his thumb or finger through the aperture 30 and the ring 32 into contact with the bottom 22 of the can. The user alternately forces in and releases the bottom 22 to force the oil through the spout 20. When the user is through with the can 6, he places the can in substantially an upright position on a supporting shelf, or the like. In the event the can 6 is partially tipped over, or is not deposited in a substantially vertical direction, the can will momentarily rest on the side wall 28 of the base member 10. However, as long as the center of gravity X of the can 6 is not moved over the point of contact of the wall 28 with the supporting surface, the can 6 will right itself, that is, turn back to a vertical position.

In a commercial construction it is preferred that a sufficient amount of weighting material 38 be deposited in the chamber 36 to position the center of gravity X below the bottom 22 when the can is filled with oil, such that the can 6 will right itself even if tilted all the way over on its side. The heavier the weighting material 38, as compared with the remaining weight of the can 6, including the contents of the can, the lower will be the center of gravity X, and the greater the degree which the can may be tilted and right itself. As a rule of thumb, sufficient weighting material should be provided to position the center of gravity of the can, when empty, about half way up the side walls 28.

The can 6 may be modified as illustrated in Fig. 2 by securing an elongated button 40 on the lower face of the bottom 22 at the center of the bottom 22. The button 40 extends downwardly through the ring 32 and is of a length to terminate slightly above the bottom of the base member 10, such that the button will not interfere with the support of the can 6 by the base member 10. The button 40 facilitates the movement of the flexible bottom 22 of the can 6 for forcing oil out of the spout 20. By use of the button 40, the user merely presses on the lower end of the button and does not extend his thumb or finger any substantial distance through the ring 32. Also, I prefer to secure a circular plate of flexible material 41 in the aperture 30 over the lower end of the button 40 to exclude dirt and other foreign matter from the ring 32. The lower end of the button 40 may be in contact with the upper face of the plate 41.

Another type of oil can 42 is illustrated in Fig. 3 and comprises a hollow body member 44 of circular cross-section and a base member 46. The body member 44 has a flat solid bottom 48 which would normally support the can 42 in an upright position. The top wall 50 of the body 44 is extended upwardly around the outlet aperture 52 to form a threaded extension 54. The outlet 52 is substantially smaller in diameter than the inner diameter of the main portion of the body 44. An oil dispensing mechanism 56 is secured in the outlet 52 to remove oil from the body 44. The dispenser 56 is provided with an outwardly and downwardly extending circumferential flange 58 which is threaded or crimped for threaded connection with the extension 54 at the upper end of the body 44. The pumping portion 60 of the mechanism 56 extends downwardly into the lower portion of the body 44. A suitable handle 62 extends from one side of the mechanism 56 in order that the

user can manipulate and hold the can 42, and a suitable lever 64 is extended from the mechanism 56 over the handle 62 for operating the pumping portion 60 of the mechanism 56. It will be understood that the mechanism 56 may be of any standard design to pump oil from the body 44 through a spout 66 when the user raises and lowers the lever 64.

The base member 46 of the can 42 is also circular in cross-section and is secured to the lower end of the body 44 in any suitable manner, such as by welding 68. The side walls 70 of the base member 46 are curved downwardly and inwardly (in the same manner as the side walls 28 of the base member 10 previously described) to support the can 42 when the can is tilted. The side walls 70 are flattened at 72 to form a substantially flat supporting surface 74 in the bottom center of the base member 46. The diameter of the flat supporting surface 74 is substantially less than the diameter of the body 44 and is preferably no greater than one-third the diameter of the body 44. A plate 76 is secured in the base member 46 slightly below the tops of the side walls 70 to hold a weighting material 78 in the base member 46. It will also be observed that the plate 76 may be eliminated and the weighting material 78 will be covered by the bottom 48. However, I normally prefer to use the plate 76, since the base is ordinarily made separately from the body 44. The weighting material 78 positions the center of gravity (not shown) of the container 42 on the center line of the can substantially below the bottom 48 of the body 44 to provide a self-righting action for the can 42 in the same manner as previously described in connection with Fig. 1. The amount of the weighting material 78 and the weight of the material 78, as compared with the weight of the remainder of the can 42, determines the height of the center of gravity, and the lower the center of gravity, the greater angle to which the can 42 may be tilted before the can will fail to right itself.

The containers, including the base members, shown in Figs. 1-3 are normally formed out of a metal, although they may be formed out of any desired material, so long as the containers and base members will not break or crack when inadvertently dropped or knocked over.

Still another form of container 80 is illustrated in Fig. 4 and comprises a hollow body member 82 substantially circular in cross-section and having a flat bottom 84 extending across the lower end thereof. A nozzle 86 is formed in the upper end of the body 82 to provide an outlet 88 having a diameter substantially smaller than the inner diameter of the lower portion of the body 82. It will thus be observed that the body 82 may be tilted a substantial distance before liquid in the body 82 will pour out of the nozzle 86. A base member 90 is secured on the lower end of the body 82 in any desired manner. For example, the base member 90 may be provided with a top wall 92 which is secured flush against the bottom 84 of the body 82 by a layer 94 of cement or glue or the like. A weighting material 96 having a weight greater than the remainder of the container 80 is deposited in the base member 90 to retain the center of gravity of the entire container 80 below the bottom 84 of the body 82 in the same manner as previously described. The base member 90 is preferably circular in cross-section at its upper end to conform to the configuration of the lower end of the body 82, and the side walls 98 of the base member 90 are curved downwardly and inwardly in the same manner as the base member 46 described in connection with Fig. 3, such that the container 80 will right itself when tilted to a substantial angle. The body 82 and base member 90 are formed out of a material which will withstand substantial shocks and not be shattered or broken when inadvertently knocked against any solid object. For example, the body 82 and base member 90 may be formed out of a suitable plastic material. Also, the body 82 may be formed out of a slightly elastic ma-

terial, such that the contents of the container 80 may be forced through the nozzle 86 by pressing inwardly on the side walls of the body 82.

From the foregoing it will be apparent that the present invention provides a novel self-righting container for liquids which may be tilted to a substantial angle and will right itself to prevent spillage of the contents of the container. A container constructed in accordance with this invention will occupy substantially the same storage space as a conventional container and has no outwardly extending projections thereon to interfere with handling the container in a conventional manner. An oil can or other container constructed in accordance with this invention will be simple in construction and may be economically manufactured.

Changes may be made in the combination and arrangement of parts or elements as heretofore set forth in the specification and shown in the drawings, it being understood that changes may be made in the precise embodiments disclosed without departing from the scope and spirit of the invention as defined in the following claims.

I claim:

1. A self-righting oil can, comprising a hollow body having a spout in the upper end thereof forming an outlet of a diameter smaller than the inner diameter of the lower portion of the body and having a substantially flat bottom, at least the central portion of said bottom being

flexible for forcing oil through the spout when the bottom is manually pressed, and a base member circular in cross-section and secured around the lower edge of the body, said base member having its sides curved downwardly and inwardly and having a vertical bore through the central portion thereof in communication with the central portion of the bottom of said body, said base member also having a weight sufficient to position the center of gravity of the entire can below the bottom of the body.

5 2. An oil can as defined in claim 1 characterized further in having an elongated button secured to the central portion of the bottom of the body and extending downwardly through said bore, said button being of a length 10 to extend only partially through said bore and terminate above the bottom of the base member.

15 3. An oil can as defined in claim 1 characterized further in that said base member has an annular-shaped chamber therein around said bore, and a finely divided 20 weighting material in said chamber providing a ballast for weighting the base member.
